CLAIM

The ornamental design for a liftgate trim lower, as shown and described.

DESCRIPTION

FIG. 1 is a front perspective view of a liftgate trim lower showing our new design;

FIG. 2 is a front view thereof;

FIG. 3 is a rear view thereof;

FIG. 4 is a side view thereof;

FIG. 5 is an opposite side view thereof;

FIG. 6 is a top view thereof; and,

FIG. 7 is a bottom view thereof.

It will be understood that the broken lines shown in the drawings illustrate portions of the liftgate trim lower that form no part of the claimed design.
